DISPLAY CASE

William Ardito, Springfield, Mass., assignor to
Westinghouse Electric & Manufacturing Com-
pany, East Pittsburgh, Pa., a corporation of
Pennsylvania

Application January 10, 1939, Serial No. 250,219

6 Claims. (Cl. 62—89.5)

This invention relates to refrigerator cabinets and more especially to refrigerated display cases.

It is an object of this invention to provide a refrigerated display case in which dehydration of 5 the foods displayed therein is minimized.

A further object of the invention is to provide a refrigerated cabinet of the type described having upper and lower compartments each of which is maintained at a substantially uniform temperature and the refrigeration of one of which may be materially reduced.

It is another object of my invention to provide a novel and useful arrangement of the cooling ducts in a display case of the forced air circulation type.

These and other objects are effected by my invention as will be apparent from the following description and claims taken in connection with the accompanying drawings, forming a part of 20 this application, in which:

Fig. 1 is a vertical section of a refrigerator embodying the invention taken on the line I—I of Fig. 2;

Fig. 2 is a vertical section of the refrigerator taken on the line II—II of Fig. 1; and,

Fig. 3 is a schematic drawing showing the air passages in the refrigerator and the direction of air flow therein.

Referring now to the drawings, the reference 30 numeral 10 represents a refrigerator cabinet having an upper compartment 11 and a lower compartment 12. A cooling unit 13 is disposed between the compartments 11 and 12 and is supported in a slightly inclined position between 35 two air ducts 14 on opposite sides of the refrigerator. The cooling unit 13 comprises spaced strips of metal 15 through which a refrigerant carrying tube 16 is passed back and forth. A shelf 17 comprising spaced metal bars 18 is sup- 40 ported immediately above the cooling unit 13, and metal pans 21, for the materials to be displayed, are supported on the shelf 17. A drain baffle comprising a series of Z-shaped bars 23 is secured in an inclined position below the cool- 45 ing unit 13 and conveys the moisture dripping from the unit 13 towards the front wall of the refrigerator and permits it to drip into a trough 25. The trough 25 is provided with a pipe 26 through which the condensate drains into a water 50 pan 27 in the bottom of the lower compartment of the refrigerator. The water pan 27 is pro- 55 vided with a drain pipe 28, the entrance opening 29 of which is elevated above the bottom of the pan 27 so that a portion of the water is retained in the pan 27 to humidify the air in the refrig-

erator. A perforated false bottom 31 for the lower compartment 12 is supported by inturned flanges 32 on the edges of the water pan 27.

Front walls 33 and rear walls 34 of the upper compartment 11 are sloped and the front wall 33 is provided with windows 35 through which customers may view the merchandise displayed on the shelf 17. Rear walls 34 and 36 of both the upper compartment 11 and the lower compartment 12 are provided with doors 37 and 38, respectively, the doors 37 of the upper compartment 11 being of the sliding, glass panel type. The general arrangement of the display cabinet including the humidification scheme is fully disclosed and claimed in the copending application of R. H. Tull, Serial No. 218,270, for an Improvement in forced air cooled display case and assigned to the assignee of the present invention.

In accordance with the present invention, the air in the refrigerator is circulated to equalize the temperature in each compartment. The general direction of the air flow in the compartments 11 and 12 is preferably upward so that the air does not impinge directly upon the merchandise displayed on the pans 21, thus reducing dehydration of the merchandise.

The circulation of the air is effected by withdrawing air through a perforated conduit 42 in the top of the refrigerator and conducting it 30 downwardly through a space between a false wall 43 and a side wall 44 of the refrigerator. The false side wall 43 has a portion cut out near its bottom, which opening is closed by a curved plate 46 to provide an enlargement in the air space for a fan 39 and fan motor 41, which is energized by an electrical supply circuit 50. A horizontal partition 47 is also provided in the space in line with the fan 39 to insure that the air circulated by the fan 39 passes through the 40 storage chambers 11 and 12 of the refrigerator. The air space adjacent the side wall 44 of the refrigerator communicates with the air space below the false bottom 31 of the lower refrigerator compartment 12 and the air enters the lower compartment 12 through perforations 48 in the 45 false bottom 31.

A portion of the air is also withdrawn from adjacent the cooling unit through openings 40 in the air ducts 14 thereby by-passing the upper 50 compartment 11. The air ducts 14 communicate with the space between the false side wall 43 and the true side walls 44 of the refrigerator and add a charge of chilled air from the cooling unit 13 to the relatively warm air in this space, thereby 55

reducing the average temperature of the air therein. The function of the added chilled air is to aid in cooling the lower compartment 12 which otherwise would be too warm since it receives the 5 warmest air of the upper compartment 11 which air is further warmed in the air duct adjacent to the false side wall 43 and the air duct below the false bottom 31.

The circulation of the air through the storage 10 compartments 11 and 12 is preferably relatively slow, its speed being, for example, about 6 to 7 feet per minute. This slow rate of air circulation reduces the dehydration of the food exposed to it. The relative air temperature of the two compartments 15 may be varied by varying the relative sizes of ducts 14 and the duct 42 so that either a greater or a lesser amount of air is withdrawn adjacent the cooling unit 13.

The upper compartment 11 is intended for displaying the merchandise to the customers and the lower compartment 12 for storing the reserve supply of merchandise. At night and during holidays the merchandise in the upper compartment 11 may be removed and placed in the lower 20 compartment 12 and the motor 41 stopped by opening a switch 51 in the circuit 50, which switch deenergizes the fan motor 41 independently of the system (not shown) for supplying refrigeration to the evaporator 15. This will substantially reduce the refrigeration of the upper 25 compartment 11 and reduce the cost of operating the refrigerator.

It will be apparent that this invention provides a refrigerator in which the temperature is uniform in each compartment and in which the dehydration of the food displayed therein is reduced to a minimum. It also provides a display case having an upper compartment, the refrigeration of which may be substantially discontinued 30 to reduce the cost of operation.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as are specifically set forth in the appended 45 claims.

50 What I claim is:

1. In a display refrigerator, the combination of a cabinet, a relatively large, flat cooling unit located therein to provide storage compartments on both sides of said cooling unit, said cooling 55 unit having closely spaced air passages throughout substantially its entire area, means associated with said cabinet for propelling air, means for directing air from an extended area remote from said cooling unit in one of said compartments to said air propelling means, means for conducting air from the air propelling means to an extended area remote from the cooling unit in the other of said compartments, the air thereafter passing through the last-named compartment and uniformly 60 through the cooling unit and normally to the flat surface thereof, and means for preventing substantial quantities of air from passing around the edges of the cooling unit directly from one compartment to the other and for directing a limited amount of air from adjacent the cooling unit to said air propelling means to supply an additional quantity of chilled air to one of said compartments.

2. In a display refrigerator, the combination 75 of a cabinet, a relatively large, flat, and horizon-

tal cooling unit therein to provide storage compartments thereabove and therebelow, said cooling unit having closely spaced air passages throughout a substantial area thereof, means associated with said cabinet for propelling air, means for directing air from an extended area in the upper portion of said cabinet to said propelling means, means for conducting air from the air propelling means to an extended area in the lower portion of said cabinet, said air thereafter passing through the lower compartment and through the cooling unit normally to the flat surface thereof, and means for preventing substantial quantities of air from passing around the edges of the cooling unit directly from one compartment to the other and for directing a limited amount of air from the cooling unit to said air propelling means to supply an additional quantity of chilled air to the lower compartment. 10

3. In a display refrigerator, the combination of a cabinet, a relatively large, flat, and substantially horizontal cooling unit therein to provide storage compartments in said cabinet above and below said cooling unit, said cooling unit having closely spaced air passages throughout a substantial area thereof, a drip collector below said cooling unit comprising spaced-apart troughs, means associated with said cabinet for propelling air, means for directing air from an extended area in the upper portion of said cabinet to said air propelling means, means for conducting air from the air propelling means to an extended area in the lower portion of said cabinet, the air thereafter passing through the lower compartment, through the drip collector, and uniformly through the cooling unit normally to the flat surface thereof, and means for preventing substantial quantities of air from passing around the edges of the cooling unit directly from one compartment to the other and for directing a limited amount of air 15 from adjacent the cooling unit to said air propelling means to provide an additional supply of chilled air to the lower compartment. 20

4. In a display refrigerator, the combination of a cabinet, a relatively large, flat, and substantially horizontal cooling unit therein to provide storage compartments thereabove and below, said cooling unit having closely spaced air passages throughout a substantial area thereof, a drip collector below said cooling unit, a water pan in the lower portion of the lower compartment, and means for directing condensate from the drip collector to the water pan, means associated with said cabinet for propelling air, means for directing air from an extended area in the upper portion of said cabinet to said air propelling means, means for conducting air from said air propelling means over said water pan and to an extended area in the lower portion of said lower compartment and towards said cooling unit, said air thereafter passing through the lower compartment, through the drip collector, and uniformly through the cooling unit normally to the flat surface thereof, and means for preventing substantial quantities of air from passing around the edges of the cooling unit directly from one compartment to the other and for directing a limited amount of air immediately after it passes the cooling unit to said air propelling means to supply an additional quantity of chilled air to the lower 25 compartment. 30

5. In a display refrigerator, the combination of a cabinet, a relatively large, flat, and substantially horizontal cooling unit therein to provide storage compartments thereabove and below, 35

- 5 said cooling unit having closely spaced air passages throughout a substantial area thereof, means associated with said cabinet for propelling air, means for directing air from an extended area in the upper portion of said cabinet to said air propelling means, means for conducting air from the air propelling means to an extended area in the lower portion of said cabinet, said air thereafter passing through the lower compartment and through the cooling unit normally 10 the flat surface thereof at a speed between 3 and 20 feet per minute, and means for preventing substantial quantities of air from passing around the edges of the cooling unit directly from one compartment to the other and for directing a limited amount of air immediately after it passes the cooling unit to said air propelling means, the air passing through the cooling unit being cooled substantially uniformly.
- 15 20 6. In a display refrigerator, the combination of a cabinet, a flat cooling unit located therein to

provide storage compartments on both sides of said cooling unit, said cooling unit having closely spaced air passages therethrough, means associated with said cabinet for propelling air, means for directing air from an area remote from said cooling unit in one of said compartments to said air propelling means, means for conducting air from the air propelling means to an area remote from the cooling unit in the other of said compartments, the air thereafter passing through the last-named compartment and through the cooling unit, and means for preventing substantial quantities of air from passing around the edges of the cooling unit directly from one compartment to the other and for directing a limited amount of air from adjacent the cooling unit to said air propelling means to supply an additional quantity of chilled air to one of said compartments.
